UNITED STATES PATENT OFFICE.

DANIIL J. MAJUGA, OF MOSCOW, RUSSIA.

BOILER.

Application filed November 19, 1927. Serial No. 234,375.

My invention relates to boilers and has a particular reference to boilers used for heating buildings.

The object of my invention is to provide a boiler of a simple and compact construction with a large heating surface and with a very efficient utilization of the heat of the burned gases.

For this purpose I use a cylindrical boiler with a firebox inside and with a concentric semicircular shell between the cylinder and the firebox, this shell containing several return passages for the flue gases.

My invention is more fully described in the accompanying specification and drawing in which—

Fig. 1 is a sectional elevation of my boiler, Fig. 2 is a cross section on the line 2—2 of Fig. 1, Fig. 3 is a plan view in section, Fig. 4 is a section on the line 4—4 of Fig. 1, Fig. 5 is a front view, Fig. 6 is a rear view and Fig. 7 is a diagrammatic view of the passages for the exhaust gases, the boiler being shown developed on a horizontal plane.

My boiler consists of a cylindrical shell 1 with a cylindrical firebox 2 inside. This firebox (or fire tube) has an enlargement 3 in the front part of the boiler to provide an ash chamber for the grates 4. Back of the grates a wall 5 is placed to protect the steel shell 2.

In the space between the outer shell 1 and the fire tube 2 a semicircular shell 6 is placed supported by the end plates 7 and 8 of the boiler. This shell communicates with the fire tube 2 in the rear by means of a tubular aperture or a short tube 9 and is divided into several compartments by means of longitudinal walls 10 and 11. The walls 10 enclose a compartment or flue 12. They are provided with apertures 13 in the front of the boiler (Fig. 7) which form a communication with compartments or flues 14. The walls 11 have apertures 15 in the rear forming a communication with compartments or flues 16. The latter are provided with apertures 17 in the front formed by short tubes 18 and extending outside of the shell 1. The tubes 18 form a communication between the flues 16 and outside flues 19 formed in the brickwork 20. These flues 19 are separated by a wall 21 and extend to the rear of the boiler partly encircling the boiler 1 on the outside. At the rear they are connected to the flues 16.

the foundation brickwork 20 to the smoke stack (not shown).

The semicircular shell 6 forms two concentric water chambers 23 and 24. They are connected together at the front by a tube 25. A tube 26 extends above the boiler and connects it with the main heating pipes 27 (shown with dotted lines). The return or cold water is fed into the boiler through a flanged nipple 28 connected with the return pipe 29 (shown with dotted lines).

The boiler is covered on the outside with a layer of heat insulating material 30. The openings in the rear are covered with covers 31 and 32 provided with a heat insulating material 33 and 34, such as fire brick, tile or similar refractory material. An aperture with a cover 35 is provided for cleaning the boiler.

Openings in the front are closed with covers 36 and 37 attached with bolts 38. The cover 37 is provided with additional apertures closed with hinged doors 39, 40 and 41. The first two doors are used for inspecting the fire, adding fuel and breaking the clinkers, and the door 41 is used for removing ashes.

Important advantages of my boiler are that it has a large heating surface therefore allowing a very rapid circulation of water, so that a much smaller boiler can be used for the same amount of heating required than would be the case with an ordinary type of a boiler; also that a very complete utilization of the exhaust gases is obtained due to very long flues inside of the boiler.

I claim as my invention:

1. In a boiler, the combination with an outer cylindrical shell, of an inner cylindrical shell concentric with said outer shell, end plates at the ends of said outer shell supporting the ends of said inner shell, means to burn fuel in the front end of said inner shell, an intermediate shell between said outer and said inner shell, the walls of said intermediate shell being concentric with the walls of said other shells and being supported by said end plates, said inner shell being semicircular in cross-section and occupying the upper portion of the space between said other shells, a tubular connection between the rear ends of said inner and intermediate shells, a plurality of longitudinal partitions in said intermediate shell pro-

at the front and at the rear of said shell, tubular connections between the lower portions of said intermediate shell, and a brick-work outside of said outer shell with flues 5 connected with said last named tubular connections, said flues with all of said tubular connections, spaces in said intermediate shell between said partitions and apertures in said partitions forming continuous passages for 10 exhaust gases from the inside of said inner shell.

2. In a boiler, the combination with an outer cylindrical shell, of an inner cylindrical shell concentric with said outer shell, 15 an enlargement in the front end of said inner shell, means to burn fuel in said enlargement, a refractory brickwork between said enlargement and the rear portion of said inner shell, a semicircular intermediate shell 20 in the upper portion of the space between

said outer and said inner shells, the walls of said intermediate shell being concentric with the walls of said outer and said inner shells, end plates attached to the ends of said outer shell and supporting the ends of 25 said inner and said intermediate shells, a tubular connection between said inner and said intermediate shells, a plurality of longitudinal partitions in said intermediate shell provided with apertures arranged alternately at the front and at the rear, tubular connections between the lower portions of said intermediate shell and said outer shell, all of said tubular connections, 30 passages between said partitions and said apertures in the partitions forming continuous flues for exhaust gases from inside of said inner shell.

In testimony whereof I affix my signature.

DANIIL J. MAJUGA.
